UNITED STATES PATENT OFFICE

JOHAN GEORG SCHEER, OF LIDINGO, SWEDEN, ASSIGNOR TO SVENSKA AKTIEBOLAGET
GASACCUMULATOR, OF STOCKHOLM-LIDINGO, SWEDEN

COOKING STOVE

Application filed September 18, 1929, Serial No. 393,473, and in Sweden October 11, 1928.

The present invention refers to an arrangement in cooking stoves, in which a cooking plate constituting a heat accumulator of metal, is combined with a fireplace having a storeroom for solid fuel, the fuel storeroom being surrounded by a tube, the so-called fire tube, which supports the cooking plate, and forms an interspace in which the combustion gases escape from the fireplace. According as the 10 temperature of the fire tube varies, its length will vary, whereby the cooking plate will be raised or lowered in relation to the stove plate, which is an inconvenience.

According to the invention, this inconvenience is avoided by making the fire tube 15 separate from the other parts of the stove, so that it may expand independent of said parts. The fire tube is supported by means of an arrangement, so constructed that the 20 part of the fire tube, supporting the cooking plate, practically does not change its vertical position. Thus the position of the cooking plate will also be constant or nearly constant in relation to the stove plate. The fire 25 tube is arranged separate from the lower part of the fireplace, either from the ashpit or from a part connected with same, whereby a suitable arrangement may be placed between these parts of the stove, permitting a 30 certain movement at varying temperatures, such as a sand seal or a device similar to a packing box.

In the accompanying drawings which show 35 some different forms of carrying out the invention,

Figure 1 is a sectional elevation of my improved cooking stove,

Figure 2 is a sectional elevation similar to 40 that shown in Figure 1 but employing modified supporting means for the fire tube,

Figure 3 is a further sectional elevation 45 similar to that shown in Figure 1 but employing another modification of the supporting means for the fire tube, and

Figure 4 is a sectional elevation of another 50 form of the invention employing still another modified construction of the supporting means for the fire tube and showing the outlet pipe for the combustion gases opening in a

direction opposite to that shown in Figures 1, 2 and 3.

In Figure 1 of the drawings, 1 is the fire tube. On this fire tube is placed a cooking plate 2, which is covered by a removable cover 16, the lower part of said cooking plate serving as a fuel storeroom 17 of the fireplace 13. By means of the sand seal 3, the fire tube 1 is loosely connected with the ashpit 4. 5 is the ash outlet from the ashpit 4, and 6 an inlet for combustion air which inlet is adjustable by means of a known device, such as a screw valve 15. At its upper part, the fire tube 1 is provided with a pipe or tube 20 which forms a flue for the escape of the combustible gases and is also formed with flanges, studs or the like 7, which by means of adjusting screws 8 are supported by studs or abutments 9, which are fixed in relation to the mantle 14 of the stove.

When heated, the fire tube 1 will expand, which expansion is not transmitted to the cooking plate 2 owing to the sand seal 3. That part of the fire tube, situated above the supporting point of the studs, 7, is only very 75 slightly expanded; consequently the cooking plate 2, placed on the fire tube, will not essentially alter its vertical position in relation to the stove plate 10. On mounting the cooking stove, the position of the cooking plate in relation to the stove plate may be adjusted by means of the adjusting screws 8.

Figure 2 shows another form of carrying 80 out the invention. According to this construction the flanges or studs 7 are prolonged laterally from the fire tube 1 and extend downwards so that they keep comparatively cool, and for this reason they only expand slightly. It is evident that the cooking plate 2 in this case will also be kept at 85 a practically constant height in relation to the stove plate 10.

Figure 3 shows a third form of carrying 90 out the invention. In this construction the flanges or studs 7 have their fastening place at the lower part of the fire tube 1 but have their supporting point near to the cooking plate 2, and extend so close to the fire tube, 95 that their temperature will be nearly the

same as the temperature of the fire tube, and for this reason they expand as much as the fire tube. A loose connection 3 is arranged between the fire tube 1 and the ashpit 4 in order to prevent the transmission of the expansions of the fire tube to the cooking plate 2.

Figure 4 shows another form of carrying out the invention, in which supports 10^a extend upwards from the bottom of the cooking stove, and support the fire tube 1 by means of flanges or studs 7 and adjusting screws 8. For permitting lateral movements of the fire tube 1, the supports 10^a, by means of a joint or link 11, may be supported by a foot 12. The supports 10^a are suitably placed laterally at such a distance from the fire tube 1 and the fireplace 13, that they keep comparatively cool and are only slightly subject to varying temperatures.

The construction shows a connecting device 3 between the fire tube 1 and the ashpit of the stove, in the shape of a device similar to a packing box.

Having now described my invention, what I claim as new and desire to secure by Letters Patent is:—

1. A cooking stove comprising a cooking plate combined with a storer for solid fuel, a fire tube surrounding said storer to form a combustion chamber and to support the said cooking plate, means for exhausting the combustion gases from said chamber, means providing for the free expansion of said fire tube without substantial alteration of the position of the cooking plate relative to the stove plate and means for supporting the fire tube.

2. A cooking stove comprising a cooking plate combined with a storer for solid fuel, a fire tube surrounding said storer to form a combustion chamber and to support the said cooking plate, means for exhausting the combustion gases from said chamber, means providing for the free expansion of said fire tube without substantial alteration of the position of the cooking plate relative to the stove plate and means, supported from the bottom of the stove, for supporting the fire tube.

3. A cooking stove comprising a cooking plate combined with a storer for solid fuel, a fire tube surrounding said storer to form a combustion chamber and to support the said cooking plate, means for exhausting the combustion gases from said chamber, means providing for the free expansion of said fire tube without substantial alteration of the position of the cooking plate relative to the stove plate and means, supported from the bottom of the stove, for supporting the fire tube, said means being adjustable in a vertical direction.

4. A cooking stove comprising a cooking plate combined with a storer for solid fuel,

a fire tube, surrounding said storer to form a combustion chamber and to support the said cooking plate, means for exhausting the combustion gases from said chamber, means providing for the free expansion of said fire tube without substantial alteration of the position of the cooking plate relative to the stove plate and means, supported from the bottom of the stove, for supporting the fire tube, said means being adapted to permit lateral movements of the fire tube.

5. A cooking stove comprising a cooking plate combined with a storer for solid fuel, a fire tube surrounding said storer to form a combustion chamber and to support the said cooking plate, means for exhausting the combustion gases from said chamber, means provided at the lower part of the fire tube for the free expansion of said fire tube without substantial alteration of the position of the cooking plate relative to the stove plate and means for supporting the fire tube from the bottom of the stove.

6. A cooking stove comprising a cooking plate combined with a storer for solid fuel, a

fire tube surrounding said storer to form a combustion chamber and to support the said cooking plate, means for exhausting the combustion gases from said chamber, means providing for the free expansion of said fire tube without substantial alteration of the position of the cooking plate relative to the stove plate and means, supported from the bottom of the stove, for supporting the fire tube, said means being adapted to permit lateral movements of the fire tube, said second named means being adjustable in a vertical direction and adapted to permit lateral movements of the fire tube.

7. A cooking stove comprising a cooking plate combined with a storer for solid fuel, a fire tube surrounding said storer to form a combustion chamber and to support the said cooking plate, means for exhausting the combustion gases from said chamber, means provided at the lower part of the fire tube, for the free expansion of said fire tube without substantial alteration of the position of the cooking plate relative to the stove plate and means for supporting the fire tube from the bottom of the stove, said second named means being adjustable in a vertical direction.

8. A cooking stove comprising a cooking plate combined with a storer for solid fuel, a fire tube surrounding said storer to form a combustion chamber and to support the said cooking plate, means for exhausting the combustion gases from said chamber, means provided at the lower part of the fire tube, for the free expansion of said fire tube without substantial alteration of the position of the cooking plate relative to the stove plate, and means for supporting the fire tube from the bottom of the stove, said second named

means being adapted to permit lateral movements of the fire tube.

9. A cooking stove comprising a cooking plate combined with a stor'er for solid fuel,
5 a fire tube surrounding said stor'er to form a combustion chamber and to support the said cooking plate, means for exhausting the combustion gases from said chamber, means provided at the lower part of the fire tube, for
10 the free expansion of said fire tube without substantial alteration of the position of the cooking plate relative to the stove plate and means for supporting the fire tube from the bottom of the stove, said second named means
15 being adjustable in a vertical direction and adapted to permit lateral movements of the fire tube.

10. A cooking stove comprising a cooking plate combined with a stor'er for solid fuel,
20 a fire tube surrounding said stor'er to form a combustion chamber and to support the said cooking plate, means for exhausting the combustion gases from said chamber, means providing for the free expansion of said fire
25 tube without substantial alteration of the position of the cooking plate relative to the stove plate and means for supporting the fire tube comprising supports extending upwardly from the bottom of the cooking stove and
30 which support the fire tube by means of flanges or studs and adjusting screws thereby permitting vertical adjustment, the said supports being pivotally connected at their lower ends to support brackets secured to the
35 bottom of the stove whereby lateral movement may be imparted to the fire tube.

In testimony whereof I have signed my name to this specification.

JOHAN GEORG SCHEER.
